Primary Examiner — Elizabeth A. Albert(57) **CLAIM**

The ornamental design for a clipboard, as shown and described.

DESCRIPTION

FIG. 1 is a front perspective view of a clipboard showing my new design;

FIG. 2 is a front elevational view thereof;

FIG. 3 is a back perspective view thereof;

FIG. 4 is a left side elevational view thereof; the right side elevational view being a mirror image of the left side elevational view;

FIG. 5 is a top plan view thereof;

FIG. 6 is a bottom plan view thereof;

FIG. 7 is a front perspective view thereof folded inside out;

FIG. 8 is a front elevational view thereof;

FIG. 9 is a back perspective view thereof;

FIG. 10 is a back elevational view thereof; and,

FIG. 11 is a left side elevational view thereof, the right side elevational view being a mirror image of the left side elevational view.

The broken lines in the drawings are included to show an article in the environment that forms no part of the claimed design.

1 Claim, 10 Drawing Sheets(56)
